Attorney.

UNITED STATES PATENT OFFICE.

VINCEN P. McVOY, OF MOBILE, ALABAMA.

HOSE-NOZZLE.

1,116,094.

Specification of Letters Patent.

Patented Nov. 3, 1914.

Application filed July 8, 1913. Serial No. 777,918.

To all whom it may concern:

Be it known that I, VINCEN P. McVoy, a citizen of the United States of America, and resident of Mobile, in the county of Mobile and State of Alabama, have invented certain new and useful Improvements in Hose-Nozzles, of which the following is a specification.

This invention relates to certain new and useful improvements in hose nozzles and it has for its objects among others to provide a simple form of nozzle provided with means for producing an effective stream.

I aim further at improvements in the details of construction whereby improved results are obtained, such as providing for the control of the admission of air between the streams, the provision of a strainer of sufficient area to prevent trash or other substance from interfering with the outer stream and the provision of an extension tube or sleeve to lengthen the nozzle when necessary, and other minor details which will be more fully hereinafter set forth.

Other objects and advantages of the invention will hereinafter appear and the novel features thereof will be particularly pointed out in the appended claims.

The invention, in its preferred form, is clearly illustrated in the accompanying drawings, which, with the numerals of reference marked thereon, form a part of this specification, and in which—

Figure 1 is an elevation of a nozzle constructed in accordance with my present invention. Fig. 2 is a substantially central longitudinal section through the same. Fig. 3 is a cross section as on the line 3—3 of Fig. 1. Fig. 4 is an end view. Fig. 5 is a side elevation on a smaller scale showing an extension. Fig. 6 is a detail in longitudinal section with portions broken away. Fig. 7 is a similar view showing the parts in a different position.

Like numerals of reference indicate like parts throughout the different views.

Referring to the drawings, 1 designates the outer casing or body portion of the nozzle. It is formed at one end with the enlargement 2 internally threaded, as at 3, for attachment to the hose or an extension soon to be described in case such is employed. The enlargement 2 is provided with studs, as 4, for co-operation with a spanner, as shown. The casing or body portion of the nozzle may or may not be tapered toward

its smaller end, being shown as tapered, however, in the present instance, and its outer end is exteriorly threaded, as shown at 5, see Fig. 2, and upon this threaded portion 60 is detachably and adjustably secured the nut or end cap 6 which may or may not be corrugated or roughened for ease of manipulation, the outer end of said nut or cap portion being reduced, as seen at 7, and in some 65 instances may be provided with an annular channel 8 with which communicate the apertures 9, as seen in Figs. 1, 2 and 5, for the purpose of introducing atmospheric air at a point adjacent the outer stream soon to be 70 described. In some instances, however, this annular channel and the apertures leading thereto may not be present.

9' is a jam nut sleeved upon the threaded end portion 5 of the casing or body portion 75 of the nozzle, serving to maintain the cap or end piece in its adjusted position, in a well known way.

Within the casing or body proper 1 of the nozzle is disposed a concentric nozzle 10 80 which may be retained therein in any suitable manner, in the present instance being shown as provided at a point substantially where the taper of the outer casing terminates with an annular boss or enlargement 85 11 exteriorly threaded, as at 12, and provided with a shoulder 13, which threaded portion engages the threads 14 of the sleeve 15 introduced between the inner nozzle 10 and the outer casing 1 and providing the annular air space 16, as seen best in Fig. 2. This, however, is but one of the many ways in which these parts may be retained in relative position. The sleeve 15 may likewise be retained in position in any suitable 95 manner. In the present instance it is shown as provided at its inner end with an annular enlargement or boss 17 which at substantially diametrically opposite points is formed with depressions 18 screw threaded, as at 100 19, the said screw threads being in alignment with the screw threads 20 of the outer casing 1, as shown best in Fig. 3, and engaging these threads of the casing and the sleeve are the bushings or ferrules 21 which, 105 as will be readily understood upon reference to Fig. 3, serve to retain the sleeve and casing in relative positions, yet allowing of ready separation when necessary, also ease of assembling when setting up the nozzle. 110 The sleeve 15 is formed intermediate the bosses 17 with longitudinal channels 22, as

clearly seen in Fig. 3, which allow for the passage of the water between the sleeve and the casing.

23 is a sleeve having threaded engagement 5 with threads 24 on the casing 1, as seen clearly in Fig. 2. This sleeve 23 serves to cover the openings 25 formed in the ferrules or bushings 21 and in the sleeve 15, as seen in Fig. 3, and which afford communication 10 between the outer atmosphere and the passageway 16, so as to admit air thereto. The sleeve 23 is provided with the perforations 26 which serve to admit the air to the openings 25 and yet prevent entrance of foreign 15 substances as well as the shutting off of the inflow of air by the hand of the fireman grasping the sleeve. As seen in Figs. 2 and 3, the sleeve is enlarged in diameter interiorly between its ends, so as to provide an 20 annular chamber 27 between its inner wall and the adjacent wall of the casing 1 so as to insure sufficient air space at that point.

In some instances it is desirable to make provision against the entrance of trash or 25 foreign substances into the outer passageway 28 between the outer casing and the inner nozzle 10. This may be accomplished in a variety of ways. In the present instance I have shown a simple form of means 30 for doing this, which consists of the tapered sleeve or thimble 29 having threaded engagement with the threaded inward extension 30 of the casing and its outer end supporting in any suitable manner the inner 35 end of the nozzle 10, the said sleeve or thimble being perforated, as shown at 31, which allows sufficient water to pass therethrough into the annular passage 28. If the perforated sleeve or thimble 29 is not 40 present, the inner end of the nozzle 10 may be supported from the inner wall of the casing 10 in any suitable manner.

32 is the annular passage for the outer stream between the outer end portion of 45 the casing 1 and the sleeve 15, see Fig. 2.

The outer end of the sleeve 15 is slightly expanded or flared outwardly, as seen at 33, shown in Figs. 2, 6 and 7, the taper 7 of the inner wall of the reduced portion of the cap 50 or end piece coöperating therewith to produce an important result. When the outer end of the cap and the sleeve are flush, as seen in Fig. 2, the course of the outer stream is concentric with the inner stream. By 55 adjusting the nut outward into the position indicated in Fig. 7, the course of the outer stream is deflected inward, as indicated by the arrows in said Fig. 7, thus shortening the throw of the stream, whereas by adjusting the nut back beyond the outer end of the sleeve, as indicated in Fig. 6, the course of the outer stream is deflected outwardly.

I sometimes provide an extension to the nozzle, as indicated at 34 in Fig. 5. When 60 this is employed, its threaded end is engaged

within the threaded end 3 of the casing 1 of the nozzle in a well known manner. This extension 34 may be provided with hand grips 35, as shown in Fig. 5.

In use with the nozzle attached to the 70 hose when the water is turned on, it flows through the central nozzle 10 and through the outer surrounding passage 28 between the nozzle and the outer casing 1, passing through the channels 22 in the boss portion 75 of the sleeve 15 and thence through the annular passage 32, around the sleeve and through the passage 35 between the outer end of the cap piece 6 and the outer end of the sleeve. At the same time air is drawn in 80 through the apertures in the sleeve 23, if the latter be employed, and thence through the passages 25 into the annular air chamber 16, passing out between the inner and outer streams. The two streams are thus 85 separated by the intermediate volume of air. I have also found from practical experience that the nozzle thus constructed with the division of the stream with the intermediate air most effectually prevents popping and 90 snapping.

From the foregoing it will be seen that I have devised a simple and efficient form of nozzle and while the structural embodiment of the same as hereinbefore disclosed is what 95 I at the present time consider preferable, it is evident that the same is subject to changes, variations and modifications in details, proportion of parts, etc., without departing from the spirit of the invention or sacrificing any of its advantages. I, therefore, do not intend to restrict myself to the exact construction hereinbefore described, but reserve the right to make such changes, variations and modifications as come properly 100 within the scope of the protection prayed.

What is claimed as new is:

1. A nozzle embodying an outer casing, an inner nozzle, means for dividing a stream of water under high pressure, and means for 110 introducing air between the divided portions of the stream and preventing spraying thereof.

2. A nozzle embodying means for separating a stream of water under high pressure 115 into concentric portions and means for introducing air between such portions and preventing spraying thereof.

3. A nozzle embodying an outer casing, an inner nozzle retained therein, and means for introducing air between the nozzles adjacent their point of discharge, one of said nozzles having an adjustable end piece. 120

4. A nozzle comprising an outer casing, an inner nozzle secured therein, a sleeve intermediate the outer casing and nozzle near the discharge end thereof and spaced from said nozzle to provide an air space, and means for introducing air between the 125 sleeve and inner nozzle.

5. A nozzle comprising an outer casing, an inner nozzle secured therein, a sleeve intermediate the outer casing and nozzle near the discharge end thereof and spaced from said nozzle to provide an air space, and means for introducing air between the sleeve and inner nozzle, the said sleeve having its outer end flared.
6. A nozzle comprising an outer casing, 10 an inner nozzle secured therein, a sleeve intermediate the outer casing and nozzle near the discharge end thereof, means for introducing air between the sleeve and inner nozzle, the said sleeve having its outer end 15 flared, and a cap adjustable on the casing and having a tapered portion.
7. A nozzle comprising an outer casing, an inner nozzle secured therein, a sleeve intermediate the outer casing and nozzle near 20 the discharge end thereof, means for introducing air between the sleeve and inner nozzle, the said sleeve having its outer end flared, and a cap adjustable on the casing and having a tapered portion and provided 25 with an annular air channel in its outer face for the introduction of atmospheric air.
8. A nozzle comprising an outer casing, an inner nozzle secured therein, a sleeve intermediate the outer casing and nozzle near 30 the discharge end thereof, means for introducing air between the sleeve and inner nozzle, the said sleeve having its outer end flared, a cap adjustable on the casing and having a tapered portion and provided with 35 an annular air channel in its outer face for the introduction of atmospheric air, and perforations communicating with said channel.
9. A nozzle comprising an outer casing, 40 an inner concentric nozzle retained therein, a sleeve having its outer end flared, retained between the inner nozzle and the casing at the outer end of the latter providing an air space adjacent the discharge end 45 of the nozzle, and means for introducing atmospheric air into said air space.
10. A nozzle comprising an outer casing, an inner concentric nozzle retained therein, a sleeve having its outer end flared, retained between the inner nozzle and the cas- 50
- ing at the outer end of the latter providing an air space adjacent the discharge end of the nozzle, means for introducing atmospheric air into said air space, and a perforated protecting sleeve covering the air admission means.
11. A nozzle provided with means for dividing the stream under high pressure into concentric portions, means for admitting air between the divided streams and 60 adjusting means for controlling the outer stream, said means having an annular air chamber in its outer face.
12. The method of increasing the velocity of a stream of water under high pressure, 65 which consists in separating the stream into concentric portions, introducing air between such portions, and preventing spraying of the portions.
13. The herein described process which 70 consists in separating a stream at high pressure into concentric portions and interposing a stream of a less dense medium and preventing spraying of the portions.
14. The herein described process which 75 consists in dividing a stream of liquid at high pressure into concentric portions, introducing air between such portions, and preventing spraying of the resultant streams. 80
15. The herein described process which consists in dividing a stream of liquid at high pressure into concentric portions, introducing air between such portions, preventing spraying of the resultant streams, 85 and afterward converting the divided streams into one.
16. The herein described process which consists in dividing a stream of liquid at high pressure into concentric portions, in- 90 90 introducing air between such portions, preventing spraying of the resultant streams, and regulating the flow of the outer portion.

Signed by me at Washington, D. C., this 95
8th day of July, 1913.
